OIL BURNER

Raphael F. De Leon, Hartford, Conn.

Application April 7, 1936, Serial No. 73,083

25 Claims. (Cl. 158—90)

My invention relates to liquid fuel burners. It has among its objects to provide an improved igniter for such burners, whereby it is made possible materially to expedite and facilitate the lighting of the same. A further object of my invention is to provide improved accessible means especially adapted to use in connection with such burners despite the fact that the combustion chamber or starting wick is inaccessible, and wherein heretofore it has been necessary to light and insert a taper manually between the shells in order to light the wick. Another object of my invention is to eliminate the need for such tapers. A still further object of my invention is to provide improved means for lighting such burners, whereby it is also made possible to eliminate the smoking or sooting up thereof, as well as the blowing out of the same, all heretofore frequently experienced. Still other objects of my invention are to provide an improved fuel supply for igniting purposes together with an improved igniter wick which is readily accessible, and improved means for supplying said fluid, when desired, from said supply to said wick in the desired quantity; all while providing an exceedingly simple, convenient and safe structure readily adapted to be applied either to new burner installations or to such installations previously made. These and other objects and advantages of my improved construction will, however, hereinafter more fully appear.

In the accompanying drawings, I have shown for purposes of illustration several forms which my invention may assume in practice.

35 In these drawings—

Figure 1 is a side elevation partially in section, showing one form of my invention applied to an oil burner equipment including a plurality of burners;

40 Fig. 2 is a sectional view of a portion of the mechanism shown in Fig. 1, certain parts being omitted or broken away to facilitate illustration;

Fig. 3 is an enlarged detail sectional view of the igniting wick and the supply connection there-
45 for;

Fig. 4 is an enlarged sectional view of the pump mechanism shown in Figs. 1 and 2;

Fig. 5 is a view similar to Fig. 3 and showing a modified construction for igniting a plurality of
50 burner wicks of the same burner;

Fig. 6 is a view similar to Fig. 1, showing a modified construction embodying a modified form of igniting wick having a modified bottom fuel supply;

55 Fig. 7 is an enlarged sectional view, showing

the wick and fuel supply connections used in Fig. 6;

Fig. 8 is an enlarged sectional view of the pump used in connection with Fig. 6, and

Fig. 9 is a detail sectional view of a modified 5 form of pump mechanism.

Referring first to the illustrative structure shown in Figs. 1 to 4, it will be noted that I have therein shown a burner installation including a fuel reservoir 1 of a usual type and supplying 10 fuel through pipe connections 2 in a usual manner by gravity through the bottom of usual channeled burner bases 3, herein comprising parts of burners of a usual distillate type, generally indicated at 4 and 5, and having usual starting wicks, indicated 15 at 6, between one or more of the usual perforated shells 7; improved mechanism herein being provided whereby fuel for igniting one or more of the wicks 6 is supplied thereto in such an improved manner as to enable the same to be ignited from 20 the top of the burner, i. e., at the top of the shells 7 which constitute the flue, all as herein-after more fully described.

Referring more particularly to Figs. 1 and 4, it will be noted that the supply line 2 is connected at the reservoir side of a usual metering 25 valve 8 therein, through a pipe 9 to a pump cylinder 10, herein suitably adjustably carried, as by a band 11, at the desired height on any convenient support such, for example, as a usual reservoir supporting column 12. Herein, it will be

30 noted that a piston 13 is disposed in the cylinder 10 and normally is pressed downward into the bottom of the cylinder by a spring 14 coiled about a piston rod 15 and acting between the piston 35 13 and the top of the cylinder. As shown, this rod 15 is also provided with an operating member 16 permitting the same to be drawn up and released for return to its bottom position by the spring 14, this operating member herein being in 40 the form of a ring, while the rod may also, if desired, be suitably packed, as indicated at 17. Below the piston 13, and preferably in a base 18, inlet and outlet check valve means of any suitable construction are provided. These, in the 45 illustrative structure, are of like construction but reversed and each includes a cage member 19 in which a ball 20 and coiled spring 21 are disposed, controlling the flow through passages 22 and 23 in the member 19. As shown, one of these valves, generally indicated at A, is placed between the pipe 9 and an inlet port 24 leading into the bottom 50 of the cylinder 10, while the other valve, generally indicated at B, is placed between an outlet

55

port 25 leading out of the bottom of the cylinder and an outlet pipe 26.

Thus, it will be evident that whenever the piston 13 is pulled up, a charge of igniting fuel will be drawn from the pipe 2 through the pipe 9 up through the valve A, in such manner as to fill the cylinder 10, the valve B or outlet valve being closed during this cylinder filling operation. When, however, the member 16 is released at the limit of its upward movement, the spring 14 will automatically return the piston to its bottom position and force the charge of igniting fuel out of the cylinder and through the outlet valve B and outlet pipe 26. Thereupon, due to the action of spring 21 on ball 20, flow from the pump into pipe 26 will stop automatically.

Operatively connected to the pipe 26 are improved connections leading to my improved igniting means for the wicks. More particularly, it will be noted that herein the pipe 26 leads through improved connections hereinafter described, to the top of one of the burners, where it supplies fuel to improved accessible igniting means adapted to be suitably ignited as, for example, by a match, and further, are also adapted to carry the flame down between adjacent shells 7, herein the outer pair, to the wicks 6 between the same. Herein, I have shown in Figs. 1 to 4 such igniting means and connections for one wick of each of the burners 4 and 5 and both of these igniting means supplied from the pipe 26, but, as I am not limited to such a double construction and may also use my invention in connection with a single burner, reference will first be had to the means associated with but the one burner 4.

As illustrated in Figs. 1 and 2, the pipe 26 has a valve 27 connected therein so that in one position of the valve, fuel will flow from pipe 26 through a valve port 28 into a communicating pipe 29 and up therefrom through another pipe 30 to the burner 4. In a preferred construction, this pipe 30 is of smaller diameter than the pipe 29 and leads up along the burner, suitably spaced therefrom as desired, to the top of the shells 7. There, it is provided with a hooked upper delivery end 31 delivering transversely over the outer shell and then downward inside said shell into a vertically disposed igniting wick 32. As shown, the latter includes an outer cover or shell of suitable non-combustible wick material of absorbent character and has within the same an inner expanding core 33. This is in the form of a coiled wire suitably connected at one end, as at 34, and slidably on a depending portion 35 on the end 31, and extending throughout the length of the wick 32 in such manner as to permit a flow of igniting fluid to saturate the wick 32 from the inside and also permit any excess to be delivered on the wick 6 and in the usual channels of the burner base 3 which carry the other wick or wicks 6 and provide passage means therebetween. Herein, it will be observed that the hollow igniter member 32 thus provided has its lower end resting upon the upper edge of the wick 6 in the base 3.

As a result of this improved construction, when the igniting charge is expelled from the cylinder 10 by the piston 13, the same will be delivered through the valve port 28 up through the pipe 30 and from the latter through the end portion 35 thereon into the hollow interior of the wick 32. As a result, the fuel will flow down through the wick which, due to its absorbent character, will become entirely impregnated with the fuel from its upper to its lower end as the

liquid creeps down through the wick, while the excess liquid will be supplied to the wicks and channels as heretofore described. Consequently, if, after the igniting charge has thus been delivered to the wick 32, a match is applied to the upper end of the latter, the flame will also creep down the wick and consequently ignite the burner wick or wicks 6, all in such manner as quickly to effect the lighting of the burner. Here, it will also be observed that, the wick being protected between the shells, and remaining in contact with one wick 6, the construction is such as to be free from any tendency to blow out, while insuring quick and satisfactory lighting of the wick 6, following the touching of a match to the top of wick 32, with a minimum of smoking. Attention is also particularly directed to the fact that due to the small cross section of the pipe 30 the amount of the fuel remaining in the pipe 31, after the burner starts in operation, is so small as to eliminate the difficulty with sputtering which would result from the use of a larger pipe 31. Further, by turning the valve 27 off and the valve 8 on, it will be evident that communication between any oil remaining in the pipe 30 and the pipe 26 will be effectually cut off and that a normal operating flow will be established from the reservoir 1 through valve 8.

In the illustrative structure, the valve 27 is a plural way valve so constructed that the port 28 may be swung from communication with the pipe 29 past its off position and into communication with a pipe 31, similar to the pipe 29, and likewise connected through a small pipe 38, similar to the pipe 30, and having a like connection to a corresponding wick 32 in the burner 5. Thus, it will be evident that, after igniting the burner 4, the valve 27 may be moved into position to cut off communication with the pipe 30 and establish communication with the pipe 38 and thereby enable the pump mechanism to be again operated to supply an igniting charge to the latter burner, the main fuel supply herein being established through usual twin valves 8. Further, after both burners have been ignited, communication between the pipes 30 and 38 and the cylinder 10 and reservoir 1 may be interrupted by closing the one valve 27. Obviously, if desired, by using a like valve 27 of suitably modified construction the mechanism may also be adapted successively to supply an igniting charge to more than two burners. Also, if desired, the valve 27 may be so constructed, although this construction is not preferred, in such manner as simultaneously to supply an igniting charge to two or more burners for each operation of the pump, two or more simultaneously operative ports 28 then being provided in the valve and communicating at the same time with the inlet port or passage thereof and with different outlets and igniters in an obvious manner.

In the operation of the complete structure shown in Figs. 1 to 4, it will be evident that, with the main valve 8 in closed position and the valve 27 communicating with the igniter pipe of burner 4, pulling up and releasing the pump piston 13 will result in the delivery of an igniting charge to the igniter wick 32 and burner wick 6, both of which will be saturated with oil, while the surplus oil will run into the channels of the base 3. With the valve 8 then turned on and the top of the igniter wick 32 lighted, the flame will proceed down the wick 32 to the wick 6 and ignite the latter. Then, by further turning of the valve 27, the supply of oil to the pipe 30 can be cut off, and

upon another operation of this pump, another igniting charge may be supplied to the pipe 38 in such manner as to permit the burner 5 to be ignited in a similar manner. Further, when both 5 burners are ignited, a further movement of the valve 27 will throw the same into closed position cutting off the supply to both igniter pipes.

In Fig. 5, I have shown a modified construction which may be used if desired. Therein, instead 10 of one delivery portion 35, two such delivery portions are provided on the portion 31 of the pipe 30 and, instead of one wick 32, two such wicks are provided, each cooperating with a different wick 6 in the burner base. Such a construction enables 15 simultaneous igniting and saturation of both wicks 32 and both wicks 6 and may be used under certain circumstances. However, I find that the use of a single igniter wick is adequate under most circumstances due to the connection of the channels 20 containing the wicks 6.

In Figs. 6 to 8, I have shown a further modified construction. This is generally similar to that shown in Figs. 1 to 4 but includes a bottom liquid supply for the igniter wick and a modified pump 25 structure, as well as a modified igniter wick structure. Referring first to the pump, it will be observed that in this construction, the pipe 40 connected to the supply pipe 2 delivers laterally into a cylinder 41 near the top of the latter 30 through a check valve 42. Further, the supply from the cylinder 41 passes through a pipe 43 connected to a port 44, disposed axially of the cylinder base, and this port 44 is controlled by a needle valve member 45 on the bottom of the pump piston 46. In this construction also, suitable check 35 valves 47 are provided in the piston 46, for example, reciprocating spring connected plunger type valves adapted to be automatically closed during lowering of the piston and opened during 40 raising of the latter. Further, referring to the modified wick structure, it will be noted that the latter comprises a perforated tube 48, perforated as at 49 to permit the free lateral flow of fuel therethrough, and an outer enclosing fibrous 45 cover 50 similar to that used on the wick 32 and saturated by said flow. In the illustrative structure, this tubular member 48 has a lower uncovered end portion 51 extending down along side the wick 6 and into a suitable support carried on 50 the burner base 3. As shown, this support is in the form of an elbow 52, in one end of which the tube 51 is received and supported at the desired height, while that end of the elbow is suitably attached in an aperture 53 in the bottom of the 55 burner base; the elbow 52 also having a reduced passage 54 therethrough, supplying fuel to the tube 48 from a pipe 55 corresponding to the pipe 29 previously described.

In this construction, it will be evident that the 60 general operation of the igniter mechanism will be substantially as previously described and that the wick or fibrous member 50 may also be lighted from the top. However, the igniter fuel will here be forced from the pump up through the bottom of the burner base and up into the igniter wick 50, rather than flowing down the wick 32, but still in such manner as to saturate the wick 50 while also supplying fuel to the wick 6 and base channels. Thus, when the igniter valve 27 has 65 been turned on and the pump has been operated, the wick may be ignited from the top as heretofore, and the flame will creep down to ignite the regular wick 6. In practice, however, I prefer the top fuel supply shown in Figs. 1 to 4, the latter 70 not requiring any changes in the burner base and

being adapted to any one of a plurality of standard burners without such drilling or threading of the base as is necessary in the form shown in the construction in Fig. 6. It will, however, be understood that, if desired, I may use the pump of Fig. 8, in lieu of the pump shown in Fig. 4, in the construction of Fig. 1. Further, in this latter construction, if desired, I may also substitute a wick core of the tubular construction shown in Fig. 7, although I prefer the construction shown in Fig. 3 on account of its elimination of the small holes 49 in the tubular member 48 and any possible clogging thereof under certain conditions.

In Fig. 9, I have also illustrated a modified form of pump which may be used in lieu of the pumps heretofore described, if desired. In this construction, the pump is provided with valves corresponding in general to the valves A and B shown in Fig. 4, and also with improved tripping means for tripping these valves when the pump piston 13 is in the bottom of the cylinder 10. More particularly, it will be observed that an outlet valve having a shank 56 and a conical closure 57, normally elevated by a spring 58, is provided with an elongated slot connection 59 on the upper end of its stem, while a corresponding reversely disposed inlet valve 60, having a collar 61 on a depending stem acted upon by a spring 62, is provided with a like slotted connection 63 above the valve. Thus, with the inlet valve 60 above and controlling the inlet port 64 and the outlet valve 57 controlling an outlet port 65, and a cross arm 66 pivoted intermediate its ends at 67 and having pins 68 and 69 received in the slot connections 63 and 59 respectively, and an upstanding arm 70 on the cross member 66 projecting into the path of the piston 13, the valves 60 and 57 will be tripped in such manner that any excess oil remaining in the vertical portion of the igniter supply pipes will flow back to the pump cylinder until the oil level equalizes. Thus, for example, the oil remaining in the pipe 38 will be substantially lowered in such manner as to remove any difficulty of sputtering of oil in such a pipe even if the same is of relatively large diameter. However, due to the use of a pipe 31 of small diameter, the difficulty with sputtering is found to be eliminated in such manner as not to require the use of a pump of the special construction shown in Fig. 9.

In the use of my invention, it is possible to speed up the lighting of an oil burner substantially as compared with the two to five minutes required in connection with ordinary burners now in use and lighted by the taper method, while still maintaining the minute difference in level of the liquid in the reservoir and the burner base required under the fire regulations. Thus, for example, in certain jurisdictions where this difference in level cannot exceed $\frac{1}{16}$ of an inch, it may take up to four or five minutes to start the burner where the burner has been in use for a few months, and up to two minutes even when the burner is new. With my improved construction shown in Figs. 1 to 4, however, the flame 65 will creep down the wick in the space of a few seconds, and with the surplus of the igniting fluid supplied to the wick in the burner and the burner channels, the burner will be started in effective operation in substantially less time than 70 has heretofore been possible even with a new burner. Further, with the igniting charge metered by the pump and the igniting fuel delivered between the shells and ignited at the top so that flame must creep down the wick between these 75

shells, my improved construction is entirely safe in use. Safety is further promoted by the provision of the valve shutting off the supply to the igniter and the use of the small riser tube leading to the top of the shells, which tube can, of course, be spaced as far as desired from the shells. Attention is further directed to the fact that my improved construction, shown in Figs. 1 to 4, is adapted to use on standard burner equipments without substantial change and without any necessary change in the burner base or in the reservoir. It will also be evident that my construction is such as to be inexpensively produced and to be readily and quickly applied, while also being adapted to function satisfactorily over long periods without requiring servicing. These and other advantages of my improvements will, however, be clearly apparent to those skilled in the art.

20 While I have in this application specifically described several forms which my invention may assume in practice, it will be understood that these forms of the same have been shown for purposes of illustration and that the invention 25 may be modified and embodied in other forms, either with or without starting wicks, without departing from its spirit or the scope of the appended claims.

What I claim as new and desire to secure by Letters Patent is:

1. An oil burner having a flue and starting wick means therein comprising an igniting wick having an igniting portion adjacent the top of said flue and carrying igniting fuel to the bottom of said flue, said igniting wick having passage forming core means therein below the flue top.
2. An oil burner having a flue and starting wick means therein comprising an igniting wick 40 having an igniting portion adjacent the top of said flue, said igniting wick having therein core forming means for saturating said igniting wick laterally and providing a longitudinal flow of igniting fuel therethrough.
3. An oil burner having a flue having a combustion chamber extending to the bottom thereof, an igniting wick adjacent the top of said flue and supplying fuel to said combustion chamber, and means for supporting said igniting wick in 50 operative position in said flue having igniting fuel supply means delivering to one end of said igniting wick.
4. An oil burner having a flue having a combustion chamber extending to the bottom thereof, an igniting wick adjacent the top of said flue and supplying fuel to said combustion chamber, and means for supporting said igniting wick in operative position in said flue having igniting fuel supply means delivering to the upper end 60 of said igniting wick.
5. An oil burner having a flue having a combustion chamber extending to the bottom thereof, an igniting wick adjacent the top of said flue and supplying fuel to said combustion chamber, and an igniting fuel supply for said igniter wick including a pipe extending upward outside said flue and delivering to the upper end of said igniter wick.
6. An oil burner having a flue having a combustion chamber extending to the bottom thereof, an igniting wick adjacent the top of said flue and supplying fuel to said combustion chamber, and an igniting fuel supply for said wick including a supply pipe and a connecting delivery pipe of reduced size extending upward

outside said flue and delivering to the upper end of said igniter wick.

7. An oil burner having a flue, an igniting wick extending inside said flue and having an igniting portion adjacent the top of said flue, means for supporting said portion in said position, and means for supplying a charge of igniting fuel to said wick.

8. An oil burner having a flue, an igniting wick having an igniting portion disposed adjacent the top of said flue and delivering igniting fuel to the bottom of said flue, and means including a pump for supplying a charge of igniting fuel to said wick.

9. An oil burner having a flue, an igniting wick having an igniting portion disposed adjacent the top of said flue and delivering igniting fuel to the bottom of said flue, and mechanism for supplying a charge of igniting fuel to said wick including a pump having a piston biased to charge ejecting 20 position.

10. In an oil burner having a flue, an igniting wick having an igniting portion disposed adjacent the top of said flue and means also supplying igniting fuel into said flue below said portion, 25 and a fuel supply for supplying a charge of igniting fuel to said igniting wick including igniting fuel delivery means delivering to one end of said wick.

11. In an oil burner having a flue, an igniting wick adjacent the top of said flue and supplying igniting fuel into said flue, and a fuel supply for said igniting wick including a pump having a piston manually movable in one direction and spring means automatically operative upon release of 35 said piston to effect discharge from said pump.

12. In an oil burner having a flue, an igniting wick adjacent the top of said flue and supplying fuel thereto, means for supplying a charge of igniting fuel to said wick including a pipe delivering to one end of said wick, and means for thereafter automatically withdrawing from said pipe fuel remaining therein.

13. In an oil burner having a flue, an igniting wick adjacent the top of said flue and supplying fuel thereto, a fuel supply for said igniting wick including a pump and a pipe receiving the discharge therefrom and delivering to one end of said wick, and means for returning to said pump after operation thereof fuel in said pipe comprising inlet and outlet valve means controlling the flow through said pipe and operated upon operation of said pump.

14. In an oil burner installation, a plurality of burners having combustion chambers and shells enclosing said chambers, igniter wicks between said shells and having igniting portions adjacent the tops thereof, fuel supply connections to each of said portions, and valve means in said connections for selectively controlling the fuel supply 60 to said wicks.

15. In an oil burner installation, a plurality of burners having combustion chambers and shells enclosing said chambers, igniter wicks between said shells and having igniting portions adjacent 65 the tops thereof, fuel supply connections to each of said portions, valve means in said connections for selectively controlling the fuel supply to said wicks, and a fuel pump supplying said fuel connections.

16. In an oil burner installation, a plurality of burners having combustion chambers and shells enclosing said chambers, igniter wicks between said shells and having igniting portions adjacent the tops thereof, fuel supply connections to each 75

of said portions, valve means in said connections for selectively controlling the fuel supply to said wicks, a fuel pump supplying said fuel connections, a main fuel supply for said burners having the intake of said pump connected thereto, and selectively operable valve means controlling said burners and between the latter and said intake connection.

5 17. An oil burner installation including a burner having a flue, a reservoir out of the path of products of combustion issuing from said flue, and igniting means in said flue having an igniting portion disposed adjacent the top of said flue and delivering to the bottom of said flue,

10 and igniting fuel supply connections delivering adjacent the top of said flue and connected between said igniting portion and said reservoir including connections likewise disposed out of the path of said products of combustion and operative to deliver fuel to said igniting portion.

15 18. An oil burner installation including a burner having a flue, a reservoir out of the path of products of combustion issuing from said flue, and igniting means having an igniting portion adjacent the top of said flue and igniting fuel supply connections between said portion and said reservoir including connections likewise disposed out of the path of said products of combustion and operative to deliver fuel to said portion, said

20 connections including means for automatically withdrawing from said igniting portion fuel remaining in said connection following said delivery.

19. An oil burner installation including a burner having a flue, a reservoir out of the path of products of combustion issuing from said flue, and igniting means having an igniting portion adjacent the top of said flue and igniting fuel supply connections between said portion and said reservoir including connections likewise disposed out of the path of said products of combustion, said connections including a pipe extending upward along the outside of said flue and delivering into said portion adjacent the top

45 of said flue.

20. A burner igniting wick comprising an externally non-inflammable porous covering, and

means including a coil spring forming a core

50 within said covering for saturating the same

laterally and providing longitudinal flow of igniting fuel therethrough.

21. In combination, an oil burner having a base and a flue thereabove, and an igniting wick disposed in said flue and adapted to be supplied with oil while within said flue, said wick having its lower end disposed to ignite the oil in said burner base and having an exposed portion at its upper end disposed adjacent the upper end of said flue for lighting.

10 22. In combination, an oil burner having a base and a flue thereabove, and an igniting wick disposed in said flue and adapted to be supplied with oil at its upper end while within said flue, said wick having its lower end disposed to ignite the oil in said burner base and having an exposed lighting portion at its upper end adjacent the upper end of said flue and having provision for quickly delivering oil supplied at its upper end downwardly through the remainder of said wick.

15 23. In combination, an oil burner having a burner base and spaced flue forming shells on said base, and an igniting wick for igniting the oil in said burner base disposed in the flue between said shells and adapted to receive fuel while within said flue, said wick having its lower end adjacent said burner base and having an exposed portion adjacent the top of said shells for lighting.

25 24. In combination, an oil burner having a burner base and spaced flue forming shells on said base, and an igniting wick for igniting the oil in said burner base disposed in the flue between said shells and adapted to receive fuel while within said flue, said wick having an igniting portion disposed adjacent the top of said flue and having means for delivering igniting oil supplied at the upper end thereof quickly to said burner base while saturating said wick along the length thereof.

30 25. In combination, an oil burner having a burner base and a flue upstanding therefrom, means for supplying fuel to said base, and a fuel igniting wick in said flue including an igniting portion at its upper end and adapted to be supplied with fuel while within said flue comprising fuel absorbent means having a core permitting lateral saturation of said wick and longitudinal flow of igniting fuel therethrough.

RAPHAEL F. DE LEON. 50
